ABSTRACT OF THE DISCLOSURE

An iris type diaphragm including a single one-piece blade member having several overlapping diaphragm blades movably supported by flexible elements integral therewith, and cooperating in equiangular radial relation to one another to define a symmetrically variable aperture. The blade member is positioned in a support ring, and the blades are mounted on an adjustable disk rotatable within the support ring.

BACKGROUND OF THE INVENTION

The present invention relates to adjustable iris type diaphragms, particularly for use in photographic cameras and other types of optical apparatus, and more specifically to such diaphragms including a plurality of diaphragm blades movably supported by flexible means integral therewith, such blades preferably comprising a single one-piece blade member.

In the photographic and optical arts it is well known to employ adjustable diaphragms to vary selectively the effective aperture of a lens system, and it has long been recognized that, ideally, any aperture defined by such an adjustable diaphragm should be perfectly circular and concentric with the axis of the lens system. With a diaphragm that is adjustable infinitely over a given range of aperture sizes, it is impossible, for practical purposes, to preserve perfect aperture circularity; but such circular apertures can be satisfactorily approximated by an adjustable diaphragm in which at least three diaphragm blades, and preferably more, are pivoted at equiangular points of a circle concentric with the lens axis and are moved in unison by an adjusting ring so that the inner edges of the overlapping blades define a variable substantially circular aperture along the lens axis. As used herein, this general type of diaphragm is referred to as an "iris" diaphragm, implying its close resemblance to the related structure of the human eye.

Iris type diaphragms are employed commonly in more expensive cameras, but, as presently made, are relatively costly due to the number of parts that must be fabricated and assembled, which may include as many as ten or more diaphragm blades in each iris diaphragm assembly. Therefore, in most relatively inexpensive cameras provided with an infinitely variable diaphragm device, the advantages of an iris type diaphragm are sacrificed in the interest of economy by substituting a variable diaphragm comprising fewer parts, typically one in which two overlapping movable blades are provided with angular notches which cooperate to define a generally rectangular aperture of variable area.

SUMMARY OF THE INVENTION

The present invention is directed to simplifying and thereby reducing the cost of iris diaphragms to enable them to be employed economically in relatively inexpensive cameras. This objective is realized, in accordance with the present invention, by eliminating the mounting pins or the like customarily used to support the diaphragm blades in movable fashion and, preferably, by combining

all of the diaphragm blades in a single one-piece blade member. To assemble the preferred diaphragm structure, the one-piece blade member is positioned in a support ring; an adjusting disk is positioned in engagement with the blades of the blade member; and the support ring is attached to a mounting plate to retain the foregoing components in assembled relation. Thus, the complete iris diaphragm unit comprises only four basic components, as opposed to the many more components of a corresponding conventional iris diaphragm assembled from separate blades, pivot pins, etc. Additionally, by virtue of this novel construction, the accuracy and reliability of the assembled unit is much less dependent on critical tolerances than in the case of corresponding conventional devices, thereby further simplifying the manufacturing process.

BRIEF DESCRIPTION OF THE DRAWINGS

Various means for accomplishing the invention will be apparent from the following detailed description of a specific preferred embodiment thereof, reference being made to the accompanying drawings in which like reference numerals denote like elements and in which:

FIG. 1 is an exploded perspective view of a complete diaphragm unit according to a preferred embodiment of the invention, with the components thereof shown in horizontal positions;

FIG. 2 is an enlarged perspective view of the blade member comprising one component of the diaphragm unit illustrated in FIG. 1;

FIG. 3 is an enlarged view of the assembled diaphragm unit, corresponding to a top view of the assembled components positioned horizontally as depicted in FIG. 1, with the diaphragm blades illustrated in closed position; and

FIG. 4 corresponds to FIG. 3 and illustrates the diaphragm blades adjusted to an open position.

DETAILED DESCRIPTION

Referring first to FIG. 1, the four basic components of the subject iris diaphragm unit comprise support ring 11, blade member 12, adjusting disk 13 and mounting plate 14. The blade member 12 is illustrated most clearly in FIG. 2, and comprises a strap member 15 provided with ears 16 and 17 at its opposite ends. A plurality of substantially identical curved diaphragm blades 18, are supported along strap 15 in uniformly spaced relation by corresponding substantially identical support arms 19 integrally joined to the top edge of the strap as viewed in FIGS. 1 and 2, with the free ends of the blades being provided respectively with holes 21. As should be apparent by reference to FIG. 2, the blade member 12 can be formed very inexpensively from a stamped sheet metal blank simply by bending over the support arms 19 where they join strap member 15 and by forming right angles bends at the intersections of the blades 18 and their respective support arms 19 so that the blades lie in perpendicular relation to support strap 15.

To assemble the diaphragm unit, strap member 15 is bowed into a circle with the blades 18 pointed inwardly, as shown in FIG. 1, and is slipped upwardly into opening 22 in support ring 11, with the adjacent ears 16 and 17 received by notch 23 and with the support arms 19 accommodated by corresponding substantially identical slots 24. The adjusting disk 13 is then positioned immediately

below blade member 12 with its circular portion 25 received in opening 22 and with lever arm 26 extending outwardly through recess 27 of support ring 11. As adjusting disk 13 is moved into this position it is oriented so that its upwardly projecting diaphragm control pins 28 enter the corresponding holes 21 in the diaphragm blades 18, which can be moved slightly, if necessary, to align the

holes with the respective pins. To complete the assembly operation, mounting plate 14 is located adjacent the bottom surfaces of support ring 11 and adjusting disk 13 and is held in place by screws 29 threaded into holes 31 in the support ring. When the unit is so assembled, axial movement of blade member 12 is limited by adjusting disk 13 and by inwardly extending projections 32 on support ring 11 located adjacent the upper edge surface of strap 15. Rotatable movement of blade member 12 is prevented by the reception of ears 16 and 17 in notch 23 (see FIGS. 3 and 4). Accordingly, the blades 18 are maintained in adjacent relation to adjusting disk 13 with the resiliency of the blades serving to maintain them in engagement with the diaphragm control pins 28, thereby eliminating the need to rivet the pins or to employ equivalent means to retain the blades in engagement therewith.

When blade member 12 is bowed into circular form, the support arms 19 thereof extend tangentially from strap member 15, whereby the diaphragm blades 18 are positioned in the overlapping relation shown in FIGS. 1 and 3. As long as the blades are so positioned, they cooperate to obscure completely the circular adjusting ring opening 33, which is aligned with a larger central hole 34 in mounting plate 14 and defines the maximum effective aperture of the lens system with which the diaphragm unit is coaxially associated. However, as lever 26 is moved in a clockwise direction, the diaphragm blades 18 move outwardly in unison, by flexing the respective support arms 19, which are somewhat narrower and hence more flexible than strap 15. Accordingly, the aperture defined by blades 18 along the axis of the unit is enlarged progressively until lever 26 reaches the end of recess 27, as illustrated in FIG. 4, at which time the blades are positioned slightly beyond opening 33. By comparison of FIGS. 3 and 4, it will be recognized that a relatively small aperture defined by the blades is of generally rectangular symmetrical shape, but that the aperture progressively assumes a more nearly circular shape as its size increases. Therefore, this structure admittedly does not satisfy entirely the objective of maintaining a circular aperture at all times, but provides a substantially better compromise than can be achieved with conventional inexpensive diaphragm devices comprising only two movable blades, particularly at larger aperture openings at which the circularity of the aperture is generally of greater significance. However, it should be understood that the depicted four blade diaphragm unit is only illustrative and that a greater number of blades could be provided along the strap member and associated with corresponding control pins on the adjusting disk, whereby the aperture would more closely approximate a circle at all times, as in the case of conventional iris type diaphragm. While the number of blades that can be attached to the strap is limited by the length of the support arms in the illustrated embodiment, it should also be apparent that other blade support means could be provided to enable a greater number of blades to be attached movably to the strap, e.g. by molding the entire unitary blade member from a flexible material such as polypropylene, with the blades being attached to the strap by integrally molded hinge portions.

Although FIG. 3 illustrates the blades 18 positioned to obscure completely the opening 33 in disk 13, it is obvious that when the unit is employed as a variable iris diaphragm in a camera, the lever normally will be blocked by an edge of recess 27 at a position slightly clockwise from that shown, so that the blades will define an aperture of predetermined minimum size. However, the completely closed condition of the unit shown in FIG. 3 is illustrative of the fact that the same type of structure can also serve as a shutter or similar device in a camera or other instrument.

It should also be noted that the resiliency of the support arms 19 urges the blades 18 toward their respective positions shown in FIG. 3, thereby eliminating the need for supplemental springs or the like in applications requiring this mode of resiliently biased operation, e.g. in using the

unit as a normally closed shutter or as a variable diaphragm adapted to close automatically to a predetermined aperture setting. Similarly, by permanently bending the support arms 19, the blades 18 could be biased thereby toward the respective positions in which they define the maximum diaphragm aperture or any selected intermediate aperture.

Although the foregoing description relates to a specific embodiment of the invention, it is obvious that variations and modifications thereof can be effected within the spirit and scope of the invention. Accordingly, the present disclosure is to be considered as illustrative and not as limiting the scope of the invention which is defined by the following claims.

We claim:

1. An iris type diaphragm unit comprising:
a unitary one-piece diaphragm member including a peripheral strap member, a plurality of blade members extending inwardly from said peripheral strap member in overlapping relation to one another, and flexible blade support means at one end of each of said blade members attaching said one end to said strap member;

a blade adjusting member adjacent said blade members and including means engageable with portions of said blades spaced from said support means for moving in unison said portions so engaged; and
a supporting structure for maintaining said blade adjusting member and said diaphragm member in predetermined relation to one another.

2. The invention defined by claim 1 in which said one-piece diaphragm member is formed of resilient sheet metal material.

3. The invention defined by claim 1 in which said peripheral strap member comprises an elongate web supported in substantially circular form by said supporting structure, said blade support means comprising flexible arm members extending outwardly from said web in generally tangential relation thereto when said web is so supported.

4. An iris diaphragm unit adapted to define an aperture of variable size in concentric relation to a predetermined axis, said unit comprising:

a generally circular support member surrounding said axis;

a plurality of partially overlapping diaphragm blades extending inwardly from said support member past said axis;

flexible means integral with one end of each of said blades, said flexible means being attached respectively to said support member at equiangularly spaced points thereof equidistant from said axis;

an adjusting member adjacent said blades and angularly revolvable about said axis, said adjusting member including blade control means spaced thereon in equiangular concentric relation to said axis and engageable respectively with the ends of corresponding ones of said blades opposite the ends thereof integral with said flexible means; and

means for angularly revolving said adjusting member to vary selectively the aperture defined about said axis between portions of said blades adjacent thereto.

5. A one-piece iris diaphragm member comprising:
an elongate continuous support strap;

a plurality of flexible blade support arms having first portions integral with said strap at spaced positions along said strap, said arms further having second portions in parallel relation to said strap; and

a corresponding plurality of diaphragm blades integral with respective second portions of said arms and extending transversely of said arms with said blades disposed in substantially the same plane.

6. The invention according to claim 5 wherein said strap is of a substantially uniform cross section throughout its length.

7. An iris diaphragm comprising:
a tubular support member;
a plurality of diaphragm blades provided with flexible means integral therewith and attached to said support member at symmetrically disposed points thereof, said blades being thereby movably supported transversely of said support member in overlapping cooperating relation to define an aperture about the axis of said member; and
means for moving said blades in unison by flexing said flexible means to alter selectively the size of the aperture defined by said blades. 10
8. A one-piece iris diaphragm comprising:
a generally circular support strap of substantially uniform cross section throughout its length; 15
a plurality of diaphragm blades extending transversely of said support strap; and
blade support means for connecting each blade to said support strap, said support means comprising a flexible element having one part integral with one end of said blade and another part integral with said support strap. 20
9. The invention according to claim 8 wherein said circular support strap forms a substantially cylindrical member, and said blades extend generally inwardly of 25 said cylindrical member.
10. A one-piece iris diaphragm member comprising an elongate strap member of substantially uniform cross section throughout its length and including a plurality of flexible hinge members integral therewith at uniformly spaced positions along said strap member, a plurality of diaphragm blade members, each of said hinge members being integral with a corresponding diaphragm blade member, said blade members adapted to cooperate in overlapping relation to define an aperture variable in size in accordance with the relative positions of said blade members. 30
11. The invention according to claim 10 and further including a support ring for said strap member with said strap member supported to form a substantially cylindrical member, and said blades extend generally inwardly of 35 said cylindrical member.

12. In an iris diaphragm comprising:
a support member;
an adjusting member revolvably adjustable in coaxial relation to said support member;
a plurality of diaphragm blades engaged at opposite ends thereof with said support member and said adjusting member respectively and positioned thereby in symmetrical overlapping relation to one another to define about the axis of said members an aperture variable in size in accordance with the adjustment of said adjusting member; the improvement comprising; 5
resilient members integral with said blades for movably attaching each of said blades to said support member and for biasing said blades toward predetermined corresponding positions thereof at which said blades are in predetermined overlapping symmetrical relation to one another.
13. An iris diaphragm member comprising a single piece of resilient sheet metal material formed to define:
a support strap of substantially uniform cross section throughout its length;
a plurality of resilient arms integral with and extending from said strap in spaced relation therealong; and
a plurality of diaphragm blades, each of which is integral with a corresponding one of said arms and movably connected to said strap thereby. 15
14. The invention according to claim 13 and further including a support ring for said strap member with said strap member supported to form a substantially cylindrical member, and said blades extend generally inwardly of 20 said cylindrical member.
